(57) **CLAIM**

The ornamental design for a vehicle push bar, as shown and described.

DESCRIPTION

FIG. 1 is a front perspective view of the vehicle push bar of the present invention showing my new design with the broken lines depicting solely environmental structure and forming no part of the claimed design;

FIG. 2 is a front elevational view thereof;

FIG. 3 is a top plan view thereof;

FIG. 4 is a side elevational view thereof;

FIG. 5 is a bottom plan view thereof;

FIG. 6 is a second embodiment of the vehicle push bar of the present invention showing my new design with the broken lines depicting solely environmental structure and forming no part of the claimed design;

FIG. 7 is a front elevational view of FIG. 6;

FIG. 8 is a top plan view of FIG. 6;

FIG. 9 is a side elevational view of FIG. 6; and,

FIG. 10 is a bottom plan view of FIG. 6.
